UNITED STATES PATENT OFFICE.

CHARLES W. BOWSMAN, OF JOLIET, ILLINOIS.

KILN.

1,251,333.

Specification of Letters Patent. Patented Dec. 25, 1917.

Application filed July 12, 1917. Serial No. 180,163.

To all whom it may concern:

Be it known that I, CHARLES W. BOWSMAN, a citizen of the United States, and a resident of the city of Joliet, county of Will, 5 and State of Illinois, have invented certain new and useful Improvements in Kilns, of which the following is a specification.

My invention relates to kilns and more particularly to kilns for baking brick of the 10 vitreous type.

In kilns or ovens of this class, considerable time and labor are necessary in overhauling and renovating the structure periodically, owing to the burning-out and 15 sagging or spreading of the flue walls. Also in kilns of the well-known and common types, it is necessary to consume a large quantity of fuel for the reason that it usually requires from seven and one-half to 20 nine days to burn out or finish a "setting" of bricks in each kiln. By the use of my improved and novel structure, I am enabled to run a kiln for a longer period before repairs are necessary and such repairs as may be 25 requisite are only about fifty per cent. of those heretofore required on the well-known types of kilns. I am also enabled to economize the amount of fuel consumed and labor required, owing to the fact that the product 30 turned out by my improved structure is finished and ready for use in between four and five days, while the fuel consumption per diem during the period of baking is the same or sometimes less than required per 35 diem on other types.

Among the objects of my invention is the provision of a flue for a brick kiln that is adapted to automatically distribute the heat within the kiln so that bricks "set" or piled 40 adjacent the peripheral or outer wall or inclosing structure of the kiln receive approximately the same amount and degree of heat as those grouped about the center of the structure. Another object is the provision 45 of a flue for brick kilns that is constructed so that the opposite walls thereof are supported and braced and thereby prevented from sagging or spreading. And other objects comprise the provision of a 50 kiln flue that is easy to set up and comparatively inexpensive to manufacture so that

it will not materially add to the initial cost of the structure and is much easier and less expensive to repair; that is extremely economical to maintain and operate; and which 55 is simple in construction. I prefer to accomplish the divers objects in the manner hereinafter described. Reference will now be made to the accompanying drawings that form a part of the specification, wherein,— 60

Figure 1 is a central section, somewhat diagrammatic, of a brick kiln, showing my improvements incorporated therein.

Fig. 2 is a plan of the foundation and layout of a brick kiln constructed in this 65 manner.

Fig. 3 is a plan of a flue cover.

Fig. 4 is a longitudinal central section of my improved flue.

Fig. 5 is a section on line 5—5, of Fig. 4. 70

Referring to the drawings, wherein similar reference numerals indicate the same parts throughout the figures, it will be observed the kiln proper preferably comprises a dome-shaped structure 10, built of suitable masonry, a stack 11 for the discharge of the products of combustion from said structure, suitable fire boxes 12 arranged within the structure 10 and having feed openings 75 on the exterior thereof, and a tunnel or large flue 13 leading from the central portion of the kiln to the stack 11. The parts thus briefly described form no part of my invention, but comprise in a general way, the elements of a typical brick or like kiln, which 80 is well-known to those skilled in this art. 85

Suitable radial flues extend from the inside of the wall of the structure 10 to and discharge into the tunnel 13, adjacent the inner end of the latter. These flues are constructed substantially in the manner illustrated in Figs. 3, 4 and 5 of the drawings. It will be observed these flues preferably comprise parallel vertical walls, 20, 20 arising from a suitable foundation in the bottom of the kiln and which are separated from each other a distance sufficient to provide a longitudinally elongated space or passageway 21 between the inner surfaces of said walls. A suitable cover 22 is disposed 90 upon the upper surfaces of these walls 20 and provided with transverse slots or ports 95 100

23, down through which the heated products of combustion are adapted to pass to the flue chamber 21, from which latter they are drawn off through the tunnel 13 and discharged into the stack. The cover 22, above alluded to, preferably comprises fire brick slabs 24, of square or other rectangular shape, that are spaced from each other a distance corresponding to the width of the slots 23 by means of filler blocks 25. The upper surface of the cover 22 is in the same horizontal plane with and is adapted to form a portion of the floor of the kiln when the structure has been erected.

15 In order to balance the heat distribution, or, in other words, to equally draw off the heated products of combustion through the slots or flue ports 23, I prefer to incline the bottom of the flue chambers 21 downward from the outer ends thereof toward the center of the kiln, where the flues discharge into the tunnel. This is illustrated herein by providing an inclined way 26 in each flue and extending from end to end thereof and from one side wall to the other. The inclination of this flue bottom is such that the dimensions of a cross-section of the same, taken at a flue port 23, will be equal to the combined cross-sectional area of the flue openings between that point and the outer wall of the kiln, and the element 26, being constructed solid to the bottom of the foundation or walls 20, strengthens and reinforces the walls and prevents their sagging or bulging for a great length of time. It may be found necessary, however, at times to repair these walls 20, but the reconstruction necessary to accomplish this need not extend below the upper surface of the inclined way 26. Thus it will be seen that approximately one-half of each of the walls is protected and strengthened so that they will not require repair work done on them.

I have found it desirable, though not essential to the operation of my improved flue, to provide a "checker" or brace 27, that is adapted to be disposed transversely of the flue chamber at a point approximately one-fourth of the length of the flue away from the inner or discharge end thereof. This checker may be in the form of a slab cut keystone shape and fitted into suitable recesses or pockets 28, made opposite each other in the walls of the flue, into which the keystone may be readily fitted. This is for the purpose of checking the draft in the flue adjacent the tunnel as well as to strengthen and re-inforce the walls of the flues at a point where they are most liable to sag or warp.

It will be obvious to others skilled in this art that changes of the structure disclosed herein may be made without materially departing from the principles involved. For

example: The inclined bottom 26 of the flue need not extend entirely to the bottom of the foundation walls 20 throughout its entire length, the checker 27 may be dispensed with, or the cover may be constructed in some other manner. I do not wish, therefore, to be understood as limiting myself to the precise structure herein disclosed, and it will be understood that such changes as above contemplated may be made without departing from the scope of the invention as expressed in the appended claims.

What I claim is:—

1. In a kiln a baking chamber, peripherally disposed combustion chambers therefor, radially disposed flues the cross-sectional area and capacity whereof progressively increase from the periphery to the center of said baking chamber said baking chamber having as its only communication with said flues rows of slots positioned above said flues, and a discharge tunnel connecting with and leading from the inner ends of said flues to the exterior of said baking chamber.

2. In a kiln a baking chamber having a suitable floor, a discharge tunnel below said floor, and a plurality of flues disposed radially with respect to said baking chamber and discharging into said tunnel, the cross-sectional dimensions of which flues progressively increase toward their discharge ends and the floor of said chamber being provided with radially disposed series of slots in vertical alinement with said flues that afford the only communication between said flues and said chamber.

3. In a kiln a baking chamber provided with a suitable floor, means for heating said chamber, said floor being provided with vents extending throughout its area, and means for drawing a substantially equal volume of the vented products through each of said vents comprising flues, each of which is of progressively increasing capacity, into which said vents discharge.

4. In a kiln a baking chamber, peripherally disposed combustion chambers therefor, radially disposed flues the cross-sectional area and capacity whereof progressively increase from the periphery to the center of said baking chamber, said baking chamber having as its only communication with said flues rows of slots positioned immediately above said flues, a discharge tunnel connecting with and leading from the inner ends of said flues to the exterior of said baking chamber, and a baffle disposed in the upper portion of each flue adjacent the discharge end thereof.

5. In a kiln a baking chamber having a suitable floor, a discharge tunnel below said floor, a plurality of flues disposed radially with respect to said baking chamber and

discharging into said tunnel, the cross-sectional dimensions of which flues progressively increase toward their discharge ends and the floor of said chamber being provided with radially disposed series of slots in vertical alinement with said flues that afford the only communication between said flues and said chamber, and a baffle disposed

in the upper portion of each flue adjacent the discharge end thereof.

10

Signed at Joliet, county of Will, and State of Illinois, this 29th day of June, 1917.

CHARLES W. BOWSMAN.
